CLAIM

The ornamental design for a wireless charger, as shown and described.

DESCRIPTION

FIG. 1 is a front perspective view of a wireless charger, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front perspective view of the wireless charger in the second state;

FIG. 10 is a front perspective view of the wireless charger in the third state; and,

FIG. 11 is a rear perspective view thereof.

The broken lines in the figures are for the purposes of illustrating portions of the wireless charger, which form no part of the claim design.

1 Claim, 11 Drawing Sheets
